UNITED STATES PATENT OFFICE.

OSCAR H. PIEPER AND ALPHONSE F. PIEPER, OF ROCHESTER, NEW YORK.

APPARATUS SUPPORT.

Application filed May 31, 1919. Serial No. 301,109.

To all whom it may concern:

Be it known that we, OSCAR H. PIEPER and ALPHONSE F. PIEPER, residents of Rochester, in the county of Monroe and State of New York, have invented certain new and useful Improvements in Apparatus Support; and we do hereby declare the following to be a full, clear, and exact description of the same, reference being had to the accompanying drawings, forming a part of this specification and to the reference numerals marked thereon.

This invention has to do with supports for apparatus requiring connections for electricity, gas, water or other operating mediums, and, more particularly, with supports, or pedestals, for apparatus of the above description having conductors for the operating mediums connected with the apparatus and with sources of supply located at a distance from the pedestal, one object of the invention being the provision, in combination with a pedestal of the above character, of a base adapted to permit the conductors to be extended downwardly of the pedestal and under its lower walls, and to be passed horizontally through the base above the flooring, thereby obviating the cutting, weakening and disfigurement of the walls of the pedestal and of the flooring.

Another object is the provision in the above combination of a base which is simply and inexpensively adaptable to various numbers and sizes of conductors, as required by different installations, thus permitting a standard construction for the pedestal and cheapening the cost of manufacture and of installation of the unit. To these and other ends the invention resides in certain improvements and combinations of parts, all as will be hereinafter more fully described, the novel features being pointed out in the claims at the end of the specification.

In the drawings:

Figure 1 is a front elevation of an apparatus supporting pedestal and base.

Figure 2 is an enlarged front elevation of the lower portion of the same with a part of the pedestal wall removed to show the interior arrangements.

Figure 3 is a section on the line 3^a—3^a of Figure 2.

Figure 4 is a section on the line 4^a—4^a of Figure 2 and

Figure 5 is a side elevation of the lower

portion of a pedestal with a modified form of base.

Similar reference numerals throughout the several views indicate the same parts.

The invention is capable of various applications and is shown in the present instance in conjunction with a pedestal for supporting dental apparatus, 10 indicating the pedestal carrying a variety of suitable apparatus as for example the electrical motor 11 for operating the hand instruments, the examination lamp 12, the hot air syringe 13, atomizer bottle heaters 14, cuspidor and water supply 15 and atomizer air nozzle 16, these being all instruments which, with others, are commonly employed on such supports.

The above described apparatus are operated by various mediums, some requiring the supply of electrical current, others compressed air, the cuspidor requiring water to be supplied and discharged, while a supply of gas is desirable. In Figure 2 the pedestal is shown with a portion of its lower wall removed to disclose within the various conductors for these operating mediums which are preferably extended down the column of the pedestal interiorly thereof to its bottom. At 17 is shown the terminal board for the electrical connections, the conductors 18 of which pass downwardly through the bottom of the pedestal and into the upturned ends of conduits 19. Similarly the water supply pipe 20, water discharge pipe 21, and gas and air conductors 22 and 23 respectively are extended downwardly through the bottom of the pedestal for connection with their respective external sources of supply or points of discharge at some distance from the pedestal.

The base for supporting the pedestal comprises a frame indicated generally at 24 having a substantially ring-shaped bearing portion or surface 25 conforming generally in outline to the base of the pedestal which rests thereon. The bearing portion 25 is supported on a flange 26 the lower edge of which rests on the flooring, a cross rib or brace 26^a being provided to strengthen the frame. Screws 27, within the base, engage the pedestal and enter the flooring to clamp the base between the pedestal and floor and maintain the parts in proper relative position. The flange of the base has formed therein, preferably on one side, a plurality

2
of apertures 28, as determined by the number and sizes of the various conductors to be accommodated, and the latter are turned horizontally, passing below the walls of the 5 pedestal and to their respective openings in the flange of the base, being thence led above the floor to their various external connections.

By means of this construction the lower 10 walls of the pedestal are left unbroken, and are therefore stronger and more slightly than would be the case were they cut for the passage of the conductors therethrough, instead of through the base. Cutting of the flooring 15 is also obviated, provision being made for conveniently passing the conductors under the pedestal and over the surface of the floor to connection with their conduits in the side walls of the room. Furthermore this arrangement 20 permits the pedestal to be manufactured in a standardized form, the provision for the exit of the conductors being made in the base, which is preferably a casting of simple and inexpensive character 25 readily adaptable to the requirements of each installation. The construction also facilitates changes in the number or character of the conductors in that the base may be removed and formed with larger or additional 30 apertures as the case may require, this being accomplished much more readily and economically than would be the alteration of the pedestal itself.

The base securely supports the conductors 35 in their proper relative positions, as well as excluding dirt, and adds to the finish and pleasing aspect of the lower portion of the pedestal.

We claim as our invention:

40 1. A dental apparatus comprising a hollow pedestal adapted to support dental apparatus, conductors in said pedestal for operating mediums for said apparatus extending downwardly through the pedestal to external sources of supply, and a supporting 45 base for the pedestal and conductors including a frame having a bearing portion for the

pedestal and a flange for supporting said bearing portion and pedestal in spaced relation with the floor on which said flange rests, 50 said flange having openings therein for the passage of said conductors through the bottom of said pedestal and through the flange above the floor.

2. The combination with a dental apparatus support comprising a hollow pedestal, a plurality of dental apparatus thereon, and a plurality of conductors in said pedestal for operating mediums for said apparatus extending downwardly through the pedestal 60 to external sources of supply, of a supporting base for the pedestal and conductors comprising a bearing surface for the pedestal having an opening therein and an apertured flange supporting said bearing surface 65 and pedestal in spaced relation with the floor on which the flange rests, said conductors passing downwardly through the bottom of said pedestal and the opening in said bearing surface and outwardly through the apertures in said flange above the floor, and securing means for retaining the pedestal and base in position relative to each other and to the floor.

3. The combination with a dental apparatus support comprising a hollow pedestal for the apparatus, a terminal board in said pedestal for electrical conductors for said apparatus, conductors passing from said board downwardly through the bottom of the pedestal, and fluid conductors for said apparatus passing downwardly through the bottom of said pedestal, of a supporting base for the pedestal and conductors comprising a bearing portion for the pedestal and an apertured flange supporting said bearing portion and pedestal in spaced relation with the floor on which the flange rests, said electrical and fluid conductors passing under the sides of the pedestal above the floor and through the apertures in said flange to external sources of supply.

OSCAR H. PIEPER.
